UNITED STATES PATENT OFFICE.

ALBERT SILVER, OF ELLIS, KANSAS.

SAFETY-BRIDGE.

1,169,517.

Specification of Letters Patent. Patented Jan. 25, 1916.

Application filed June 30, 1915. Serial No. 37,399.

To all whom it may concern:

Be it known that I, ALBERT SILVER, a citizen of the United States of America, residing at Ellis, in the county of Ellis and State of Kansas, have invented certain new and useful Improvements in Safety-Bridges, of which the following is a specification, reference being had therein to the accompanying drawing.

10 This invention relates to a safety bridge for stock cars, and has for its principal object the production of a bridge which is adapted to span the space between the floor of a stock car and the end of the run of the 15 usual or ordinary stock pen, whereby the stock may be driven into the car or driven therefrom without danger of becoming injured or maimed, since they can walk upon the bridge which will prevent their being 20 caught between the car and the end of an ordinary stock pen.

Another object of this invention is the production of a safety bridge wherein simple and efficient means have been provided 25 for the retaining of the bridge in an adjusted set position in engagement with the stock car.

Another object of this invention is the production of a bracket having a chain secured thereto, this bracket being adapted to 30 be secured to a safety bridge for stock cars, wherein the chain may be adjusted according to the length desired and retained in a set position so as to retain the bridge at a 35 desired height.

With these and other objects in view this invention consists of certain novel combinations, constructions, and arrangements of parts as will be hereinafter fully described 40 and claimed.

In the accompanying drawing: Figure 1 is a perspective view of a safety bridge having the retaining elements secured thereto, and illustrating the manner in which the 45 same is used. Fig. 2 is a sectional view through a safety bridge showing the retaining means in side elevation. Fig. 3 is a top plan view of the retaining means showing the same mounted upon a portion 50 of the safety bridge. Fig. 4 is a detailed perspective view of the bracket. Fig. 5 is a longitudinal sectional view through the bracket, showing the same mounted upon a portion of the safety bridge.

55 Referring to the accompanying drawing by numerals it will be seen that the stock car

1 is provided with the usual bottom 2 having the door frame 3. The safety bridge 4 is elongated so as to have its end portions extending for a distance beyond the side 60 portions of the door frame 3, as clearly shown in Fig. 1. Adjacent the rear side edge and at each end of the safety bridge 4 there is formed a notch 5, which is adapted to fit around one side portion of the door 65 frame 3, whereby the inward movement of the bridge into the car will be limited, while a portion of the bridge will rest upon the floor 2, as clearly shown in Fig. 2.

The bracket 6 comprises an elongated body 70 having the apertures 7 formed therein so as to allow the screws 8 or other securing means to be passed therethrough for fixedly retaining the bracket 6 in a desired position upon the safety bridge 4. The body of this 75 bracket 6 is provided with the upwardly extending lip 9 at one end, having the V-shaped notch 10 formed therein, so as to provide the claws 11. These claws extend slightly rearwardly, as shown clearly in 80 Figs. 2 and 5, for purposes to be hereinafter set forth. The opposite end of the body of the bracket 6 has a coiled tongue 12 formed thereon, to which the ring 13 is secured. A 85 chain 14 is carried by this ring and is provided at its opposite end with the hook 15. It should, of course, be noted by referring particularly to Fig. 1, that the bracket 6 and chain 14 as above set forth are adapted to be carried adjacent each end of the 90 bridge 4.

When this device is in use it may be lifted by means of the handle 16 which is secured thereto in any suitable manner, so as to have the notched portions 5 adjacent the end 95 thereof engage the door frame 3. The hook 15 may then be passed around the door frame, as clearly shown in Figs. 1 and 2, at which time the chain may be drawn tautly so as to be passed down into the notch 10 and thus carried by the claws 11. Since these 100 claws extend slightly rearwardly they will positively prevent the chain from slipping and will hold the same so as to retain the safety bridge in a desired set position as 105 shown clearly in Figs. 1 and 2. The slackening portion of the chain may be drawn to one side so as not to interfere with the operation of this invention, but when it is necessary the entire chain may be used so as 110 to allow the safety bridge to be swung downwardly as far as desired. It will be

seen however, that the chain may be positively retained for carrying the safety bridge in a desired position by means of the claws between which it is necessary for the bridge to pass. Therefore, it will be seen that a very simple and efficient bracket and chain have been provided for holding the bridge in a desired set position according to the height at which the bridge must be retained.

10. What is claimed is:

1. In a safety bridge for stock cars the combination of a bracket comprising an elongated body, said body being adapted to be carried upon a safety bridge, a lip formed upon said bracket and extending upwardly and slightly rearwardly therethrough, said lip provided with a V-shaped notch thereby forming a pair of claws, a chain secured to said bracket and provided with a hook, said hook being adapted to engage a door frame of a stock car at which time said chain may be drawn tautly and passed into said notch of said lip so as to be engaged by said claws, whereby said chain will be held at a desired

length so as to retain a safety bridge in a 25 desired set position.

2. In a device of the class described, the combination of an elongated body, said body being adapted to be secured to a safety bridge, said body having a coiled tongue 30 formed upon one side thereof, a ring carried by said tongue, a chain carried by said ring, and provided with a hook, said body provided with a laterally extending lip at its opposite end, said lip extending upwardly 35 and slightly rearwardly, said lip provided with a V-shaped notch thereby forming claws, said hook being adapted to engage the door frame of a stock car, at which time a portion of the chain may be drawn tautly 40 and passed between said claws, whereby said claws will positively engage the chain for holding the same from slipping, and thereby retaining a safety bridge in a desired set position.

In testimony whereof I hereunto affix my signature.

ALBERT SILVER.
